UNITED STATES PATENT OFFICE.

ALBERT P. LEE, OF CHICAGO, ILLINOIS, ASSIGNOR TO LEE LOADER & BODY CO., OF CHICAGO, ILLINOIS.

DUMPING-HOPPER.

1,253,059.

Specification of Letters Patent.

Patented Jan. 8, 1918.

Application filed October 13, 1916. Serial No. 125,346.

To all whom it may concern:

Be it known that I, ALBERT P. LEE, a citizen of the United States, residing at Chicago, in the county of Cook and State of Illinois, have invented a certain new and useful Improvement in Dumping-Hoppers, of which the following is a full, clear, concise, and exact description, reference being had to the accompanying drawings, forming 10 a part of this specification.

My invention relates to dumping hoppers and has for its object the provision of an improved hopper of this nature which is adapted by rolling to either side of its central position to discharge the load to either side.

My improved hopper is of great utility in connection with vehicles, although its use of course is not so limited. In general this 20 invention relates to the means employed to cause a substantially automatic dumping movement of the hopper to either side of its central position. In order to arrange the hopper to automatically discharge its load 25 I find after much experiment that a structure should be employed whereby the center of gravity of the material may be gradually lowered as the hopper moves from its central position to a discharge position. I find 30 that I get a peculiarly satisfactory structure to accomplish this end by inclining the runway on which the hopper rolls and at the same time having the outline of the rail or other portion of the hopper which coöperates 35 with the runway of a compound curve instead of being circular. Furthermore, the hopper when it reaches its limited position is provided with means whereby it tilts about a pivotal point, the momentum which 40 the hopper gains in rolling down the runway serving to enhance the effect of the pivotal point by bringing one side of the hopper suddenly to rest so that it can act as a pivotal point for the entire hopper.

45 I will explain my invention more in detail by referring to the accompanying drawing, in which Figure 1 is an end view of a vehicle provided with a hopper constructed in accordance with my invention; and

50 Fig. 2 is a fragmentary sectional view of the runway and the hopper more clearly to illustrate the principles involved.

Referring more particularly to Fig. 1 I show a vehicle 1 upon which the hopper 2 is carried, this hopper being adapted to roll to

either side of its central position to a limiting discharge position, one discharge position being shown in dotted lines. The hopper itself may be held in its central position by means of toggle arms 3—3 or in any other suitable manner, and may also be locked further in its central position by the bolt 4 when desired. The object of the structure which I will presently explain is to permit the hopper practically to roll automatically from its central position to either discharge position when the said hopper is given a slight push to start it on its way. A suitable limit chain 5 of course prevents the hopper from going further than its limiting 70 position, which chain coöperates with other instrumentalities as will presently appear. A runway 6 is provided upon which the hopper rolls, this runway sloping from the center downwardly to either side. The extremities of the runway are provided with fingers 7—7 which fingers coöperate with pins 8 to permit of a tilting or pivotal movement of the hopper when at its limiting position, the chain 5 coöoperating with the 80 structure. The hopper body itself is provided with a rail 9 which rail may or may not conform throughout more or less of its length to the actual outline of the hopper bottom, it being shown in this instance as co-operating throughout quite a large portion 85 of its length except at the sectors 10—10. Blocks 11 may be inserted between the sectors and the rail to maintain a strong and rigid structure. This rail 9 is not constructed in the form of a circle. The actual form which this rail would take if constructed circularly is represented by the line 12. In practice, however, I find that I obtain the benefits previously mentioned by 95 drawing the bottom of the hopper from centers 13—13, the left hand center 13 serving as a focus for the right hand portion of the rail, and the right hand focus 13 serving for the left hand portion of the rail. It will 100 thus be seen that as the rail extends upwardly it is drawn inwardly from the position it would occupy if it were a true circle. I do not of course mean to say that the rail sections have to be circles, but it is readily 105 apparent that the spirit of the invention is to have the rail as it extends upwardly extend inwardly from the position it would occupy if it were a true circle. I have found, however, in practice that the compound 110

curve formed by two arcs of circles serves the purpose and I have thus illustrated it as one embodiment of my invention. It will be readily apparent for instance, that the 5 center of gravity of the hopper and contents is lowered as it rolls from its central position to its discharge positions, or at least that the center of gravity is not unduly raised by reason of the construction outlined. If we should assume the hopper circular, for instance, and assume the runway straight, then if the hopper of Fig. 2 rolls to the left a certain distance the point 14 10 would coincide with the point 15. By reason 15 of my construction, however, when the hopper has rolled that distance to the left the point 16 coincides with the point 17, thus showing a lowering of the hopper and contents and thus a consequent lowering of the 20 center of gravity in these two cases which is proportional to the distance between the points 14 and 16 plus the distance between the points 15 and 17.

From the above it will be readily clear 25 that I have provided a structure by virtue of which I obtain a substantially automatic movement of the hopper from its central to its discharge positions; at any rate within practical limits it requires very much less 30 power or effort to move the hopper from its central position to its discharge position with my construction than if a straight rail and a circular outline were used. Under

such conditions actual efforts of a considerable amount would be required to effect the 35 dumping operation.

Having thus described one embodiment which my invention may take, what I claim as new and desire to secure by Letters Patent is:

A device of the character described comprising a runway whose opposite sides slope downwardly, a rolling hopper adapted substantially automatically to roll downwardly on either side of said runway from its central charge carrying position to either discharge position, said hopper having exteriorly thereof and about its periphery a curved rail co-operating with said runway whose extremities slope inwardly of the position they would occupy were said rail a true circle, and means whereby said hopper when it reaches the limit of its rolling movement pivots to completely discharge its load, said hopper having a widely flaring mouth, and having portions of its bottom extend along lines substantially forming sectors of the 50 curved rail.

In witness whereof, I hereunto subscribe my name this 29th day of September, A. D. 60 1916.

ALBERT P. LEE.
